UNITED STATES PATENT OFFICE.

FRANZ GUSTAV SEYFFARTH, OF NEWARK, NEW JERSEY.

DOOR-LOCK.

No. 866,893.

Specification of Letters Patent.

Patented Sept. 24, 1907.

Application filed February 11, 1907. Serial No. 356,858.

To all whom it may concern:

Be it known that I, FRANZ GUSTAV SEYFFARTH, a citizen of the United States, residing at Newark, in the county of Essex and State of New Jersey, have invented certain new and useful Improvements in Door-Locks; and I do declare the following to be a full, clear, and exact description of the invention, such as will enable others skilled in the art to which it appertains to make and use the same.

10 My invention relates to improvements in door locks and especially with reference to the construction of the latch bolts and co-operating devices, whereby the door, when latched, may be opened by merely pressing against the same in the required direction and without the necessity of employing knobs or the like devices for operating the latch, and my invention consists 15 in the construction, operation and arrangement of devices hereinafter described and claimed.

In the accompanying drawings,—Figure 1 is an elevation of a lock embodying my invention, with one side of the casing removed, and showing the pivoted key-actuated locking bolt in unlocked position in full lines and in locked position in dotted lines; Fig. 2 is a horizontal, longitudinal sectional view of the same, 20 taken on the plane indicated by the line *a—a* of Fig. 1; Fig. 3 is a detail vertical sectional view of the same, taken on the plane indicated by the line *b—b* of Fig. 1; Fig. 4 is an elevation of a modified form of my improved lock, with one side of the casing removed; Fig. 25 5 is a similar view, showing another modification; Fig. 6 is a detail elevation showing another modification; and Fig. 7 is a detail sectional view, taken on the plane indicated by the line *c—c* of Fig. 6.

The latch bolt 1 is longitudinally movable, and is 35 beveled on one side, at its outer end, as at 2, to provide a cam surface, which when the door is closed, strikes the usual keeper, not here shown, and causes the latch bolt to move inwardly, against the tension of its spring, to clear the keeper, then returning the latch bolt to its initial position, to cause it to engage the keeper and coat therewith to keep the door closed.

The lock case 3, which may be of the form here shown, or of any other suitable form, is provided on its front edge or wall with an opening 4 for the passage of the 45 latch bolt. Abutments 5 are on the inner side of said front wall, immediately above and below the latch bolt. The latter has, near its straight edge 6, pivot studs or fulcrum 7, which project from the upper and lower sides of the latch bolt, and when the latter is in 50 its normal, extended position, bear against the said front wall, between the said abutments and one of the side walls. Said studs enable the latch bolt to turn in the direction indicated by the arrow in Fig. 2 to enable the door to be unlatched by pressure against one 55 side thereof. The latch bolt is reversible, as will be

understood, to enable the lock to be used on either right or left-hand doors.

A follower 8 engages the inner end of the latch bolt, the latter being free to turn angularly with reference to the follower, and in opposite sides of the follower 60 are longitudinal guide grooves 9, which are engaged by guide flanges 10, that project inwardly from the sides of the lock case. The spring 11, which normally projects the latch bolt, bears against the inner side of the follower. Said spring, in the form of my invention shown in Fig. 1, is of inverted U-shape, one of its arms bearing against the follower and the other bearing against the key-actuated bolt 12. Said key-actuated bolt is pivotally mounted on a stud 13, has a cam recess 14 for the reception of the key, and has an arm 70 15. Near its pivot, the said bolt 12 has cam faces 16, 17, disposed at a suitable angle to each other.

When the bolt 12 is in unlocked position the spring 11 bears against the cam face 16. When the bolt 12 is turned by the key to cause its arm 15 to lie behind the 75 follower, and hence secure said follower and the latch bolt in a projected position and against inward longitudinal movement, the spring 11 bears against the cam face 17. Hence the said spring holds the said locking bolt in either of the positions in which the same may be 80 placed by the key.

In the form of my invention shown in Fig. 4, the latch bolt is indicated at 18, the follower at 19, and the spring which actuates the follower and latch bolt at 20. The key-actuated locking bolt 21 is longitudinally- 85 movable, supported by guide studs 22, and has stop studs 23 on its upper side to coat with a stud 24 in the lock case. Said locking bolt also has a detent projection 25 on its upper side. At one side of the locking bolt is a key-actuated tumbler 26, which is pivotally 90 connected at its inner end to the lock case, as at 27. Said tumbler has a detention projection 28, on which a detent spring 29 bears when the locking bolt is in unlocking position. When the said bolt is moved by the key to locking position, the detent spring bears against 95 the rear side of the detent projection 25 thereof, to hold the same in such position. When the key is operated to move the locking bolt to unlocking position, it first acts on the tumbler to raise the latter and cause its projection 28 to release the detent spring from the locking 100 bolt detent projection 25, as will be understood.

In the form of my invention shown in Fig. 5, the locking bolt 29 is independent of the latch-bolt 30. The spring 31, which bears against the follower 32 is a coiled extensible spring. The tumbler 33 and detent spring 105 34 are similar to those in the form of my invention shown in Fig. 4 and described above.

In the modified form of my invention shown in Fig. 6, the follower 35 is operated by a knob yoke 36 of ordinary form. The latch bolt 37 has a transverse slot 38 110

near its rear end, and the follower has a stud 39 which forms a loose pivotal connection between the follower and the latch bolt and operates in the said slot 38.

From the foregoing description, taken in connection 5 with the accompanying drawings, the construction and operation of the invention will be readily understood without requiring a more extended explanation.

Various changes in the form, proportion and the minor details of construction may be resorted to without departing from the principle or sacrificing any of 10 the advantages of this invention, as defined by the appended claims.

Having thus described my invention, what I claim as new, and desire to secure by Letters-Patent, is,—

15 1. A lock having a latch bolt beveled on one side at its outer end, movable longitudinally and also mounted for

lateral angular movement, a follower movable longitudinally with the latch bolt, and means to actuate said follower and latch bolt, substantially as described.

2. A lock having a latch bolt beveled on one side at its 20 outer end, movable longitudinally and also mounted for lateral angular movement, a follower movable longitudinally with the latch bolt movement, and a spring to move said follower and latch bolt outwardly.

3. A lock having a latch bolt beveled on one side at its 25 outer end, movable longitudinally and also mounted for lateral angular movement, a follower movable longitudinally with the latch bolt, a spring to move said follower and latch bolt outwardly, and means to lock said follower and latch bolt when the latter is in projected position. 30

In testimony whereof I have hereunto set my hand in presence of two subscribing witnesses.

FRANZ GUSTAV SEYFFARTH.
